DESIGN FOR A LINK FOR A WATCH BRACELET

Saul Ritter, New York, N. Y.

Application January 10, 1936, Serial No. 60,504

Term of patent 3½ years

To all whom it may concern:

Be it known that I, Saul Ritter, a citizen of the United States, residing in New York city, in the county of New York and State of New York, have invented a new, original, and ornamental Design for a Link for a Watch Bracelet, of which the following is a specification, reference being had to the accompanying drawing, forming part thereof.

Fig. 1 is a plan view of a link for a watch bracelet showing my new design;

Fig. 2 is an edge view of the same;

Fig. 3 is an end view of the link.

I claim:

The ornamental design for a link for a watch bracelet as shown.

SAUL RITTER.
